UNITED STATES PATENT OFFICE.

ALFRED STELL, OF STEETON, AND JOHN STELL, OF KEIGHLEY, ENGLAND.

DOFFING APPARATUS FOR SPINNING, DOUBLING, TWISTING, AND LIKE MACHINES.

Application filed September 15, 1920. Serial No. 410,501.

To all whom it may concern:

Be it known that we, ALFRED STELL and JOHN STELL, subjects of the King of Great Britain, and residents, respectively, of Green 5 Hill, Steeton, in the county of York, England, and 34 Devonshire Street, Keighley, aforesaid, have invented a certain new and useful Improvement in Doffing Apparatus for Spinning, Doubling, Twisting, and like 10 Machines, of which the following description, having reference to the accompanying sheets of drawings, is a specification.

Our invention relates to doffing apparatus for machines known as cap spinning, doubling, twisting and like machines, although 15 certain features thereof may be employed in connection with flyer or other spinning and like machines. Our said invention consists in an improved arrangement and construction 20 of the receptacles for the full and empty bobbins and in the devices for moving or operating the same where by the functions of doffing are performed in a simpler and more efficient manner than is the case 25 with such receptacles and their operating devices as heretofore constructed.

In order that our said invention may be readily understood, we have hereunto appended three sheets of drawings illustrative 30 thereof, to which, by figures and letters, reference is made in the following description.

Fig. 1 is an end elevation of a portion of a spinning machine having our improvements applied thereto, the different parts 35 being shown in the positions they occupy during spinning operations.

Fig. 2 is a front elevation of the parts shown by Fig. 1.

Fig. 3 is a sectional end elevation of a 40 portion of a spinning machine with our improvements applied thereto, these being shown with certain parts as moved during doffing operations.

Fig. 4 is a plan showing two of the boxes 45 or receptacles hereinafter described and the bar upon which they are mounted.

Figure 5 is a detail, rear elevation, of one of the bobbin boxes or receptacles.

Figure 6 is a side elevation of one of the 50 said receptacles.

Fig. 7 is a plan of one of our improved cap supports.

Fig. 8 is an end elevation thereof.

Figs. 4 to 8 inclusive are drawn to an en-

larged scale as compared with the other 55 views.

Similar letters and figures of reference indicate like parts throughout the several views.

A, A¹ represent the top and bottom rails 60 of the machine, and B the spindle rail, which latter is capable of being raised and lowered in the ordinary manner by means of the racks a and pinions a¹ operated from the hand wheel a² through the gear wheels a³, 65 a⁴. The spindles 1 have caps 2 mounted upon them while the lifter plate 3 is reciprocated in the common and well known manner.

We also employ the usual and well known 70 means in connection with the lifter rail whereby when doffing operations are to be performed the device for reciprocating said lifter plate 3 mechanically may be put out of gear and said lifter plate 3 operated by 75 hand.

Mounted in appropriate bearings as those 76 b¹ is a shaft b upon which are mounted gear wheels b² which gear with racks b³ while said shaft b has fixed upon it a hand 80 lever or the like b⁴ by which the shaft b is oscillated and the racks b³ raised into the position illustrated in Fig. 3 or lowered therefrom into the position shown in Figs. 1 and 2. These racks b³ carry bearings c 85 within which reciprocate racks c¹. The racks c¹ are reciprocated by pinions c² mounted upon the shaft c⁴. An appropriate handle as c³ is mounted on the shaft c⁴ by 90 which the racks c¹ may be moved towards or away from the framework C. The said racks c¹ have fixed upon them a plate d extending the length of the frame such plate d having fixed upon it at desired intervals brackets d¹ which carry a bar d² also extending the length of the machine. Mounted 95 upon the bar d² are a series of boxes or receptacles e, these also extending throughout the whole length of the frame. The boxes or receptacles are adapted to slide upon the bar d, and they are moved simultaneously lengthwise of said bar by means of the handle f fulcrumed at f¹ and engaging with projecting parts or ears e² formed or mounted upon brackets e¹ on one of the receptacles. 100 These boxes or receptacles are for the reception of full bobbins and empty bobbins y, the said empty bobbins y being supplied

to these receptacles by the operative during spinning operations when such receptacles occupy the positions indicated by Fig. 2, wherein the bobbins y are approximately 5 midway between the series of spindles 1.

One portion e^3 of each receptacle is in the form of a vertically disposed tube and is for the reception of an empty bobbin, an opening or slot e^4 being made in the base 10 and sides of said receptacles in order that same may be passed laterally over the spindles for the purposes hereinafter described. The lower flange of the empty bobbin y is supported by the part e^5 of the base of the receptacle. These receptacles, as shown by Figs. 4, 5 and 6, fit closely against each other the space intervening between one vertically disposed tube e^3 and the next forming a chamber or holder for 20 the reception of a full bobbin somewhat as shown in broken lines by Fig. 4. A notch is cut out of the end of each receptacle as shown by said Fig. 4 and the straight or regular end or surface of the neighbouring receptacle e extends alongside said notch to 25 form a slot for the purpose referred to.

Extending lengthwise the frame is a shaft h preferably rectangular in cross section such shaft having mounted upon it a number 30 of depending arms h^1 provided with extending parts or shoes h^2 these being for the purpose of supporting the full bobbins in the manner hereinafter described. Normally these parts h^1 occupy positions approximately mid-way between the series of 35 spindles 1. During doffing operations the shaft h may be moved longitudinally by its operating handle h^3 to bring said shoes opposite to said spindles and beneath the 40 flanges of the full bobbins x . The operating handle h^3 is provided with an extending pin h^4 which takes through openings in the end frame of the machine or in the bracket h^5 , and when said pin h^4 is in one 45 position in said end frame the arms h^1 and shoes h^2 are in positions clear of the bobbins x . However when doffing operations are to be performed the shaft h is moved horizontally by the handle h^3 and immediately 50 the pin h^4 is clear of the opening through which it takes the shoes h^2 are then in position opposite to or in alignment with the spindles 1.

Mounted in suitable bearings m^1 are a 55 series of racks m operated by quadrants m^2 fixed upon a shaft m^3 at one end of which is a lever arm m^4 having a handle m^5 by which it is moved. These racks m carry a plate or bar n extending lengthwise the 60 machine and having mounted upon it plates n^1 having slots n^2 of sufficient width to receive the necks 2^a of the caps 2 but sufficiently narrow to prevent vertical movement heads 2^b of said caps 2 therethrough. The 65 bar n is capable of being moved from the

position shown in Fig. 3 to a position where when the caps are raised as hereinafter described the plate will pass the necks 2^a and support the heads 2^b , while they are provided with short upwardly extending lips n^4 70 for the purpose of preventing the heads 2^b of the caps 2 from being easily dislodged from said holders n^1 . The movement of said plate n is effected by said handle m^4 which is moved from the position shown in Fig. 1 where it engages with a notch in the quadrant plate m^6 to the position wherein said lever will engage a notch m^7 in said plate m^6 . Thus the operative may easily tell when the correct amount of movement has 80 been given to said plates n^1 .

Also carried by the plate n by means of brackets o is a plate o^1 extending lengthwise the machine and to this plate o^1 are hinged at o^2 the thread guide boards o^3 and dividing plates s . Thus when said plate n is moved away from the top rail A it carries with it the parts n^1 , the boards o^3 and the dividing plates or tins s , while when said tins s are automatically moved as hereinafter described they carry with them the 90 said boards o^3 . Fixed upon the part s^1 carrying the dividing plates s is a lever t which is connected by a chain to an arm extending rearward from the spindle rail B. 95 Normally, that is when the parts are in the spinning position, the chain is somewhat slack, however when the spindle rail is lowered as during doffing operations this chain becomes tight or taut and lowers said lever t thus swinging the parts s and o^3 upon their hinge o^2 moving them from the position shown in Fig. 1 into that shown in Fig. 3 wherein the plates s are moved entirely away from the caps 2 and spindles 1. On 100 the rising of the spindle rail these parts either by gravity or assisted by counterbalancing weights or springs return to their normal positions. The chain is slack enough to allow the necessary reciprocations of the lifter plate 3 during spinning operations, while on the further lowering of said plate 3 during doffing operations said connection moves said plates s as described. 110

The usual rod v for causing the severing 115 or breaking of the threads is carried by lever arms, these being supported by the rod v^2 carried by brackets mounted upon the plate d .

The actions of our improved apparatus 120 are as follows:—

Taking it that the full bobbins have received their complement of yarn and it is desired to doff or remove same from their spindles and substitute therefor a series of 125 empty bobbins y , the handle h^3 is moved so as to withdraw the pin h^4 from its opening and carry the shoes h^2 opposite to the spindles 1 and by releasing said handle h^3 these shoes are allowed to move by gravity 130

towards said spindles 1. The spindle rail B is then raised by means of the hand wheel α^2 to a position wherein the plates n^1 are opposite the necks 2^a of the caps 2 this position of the spindle rail being determined by same coming into contact with an appropriate fixture on the framing C of the frame. The bar n is then advanced by the quadrants m to support the caps 2 in manner hereinbefore described, after which the lifter plate is raised to such a position that the shoes h^2 occupy positions between the lower ends of the full bobbins and the upper ends of the wharles 4 on which the shoes h^2 are passed beneath the bobbins' flanges, where they are held by the pin h^4 taking into another opening in the framework C formed in the proper position for this purpose. The lifter plate 3 is then lowered by hand to approximately the position shown in Fig. 3, and the spindle rail also lowered until the upper ends of the spindles 1 are slightly below the lower ends of the caps 2, the full bobbins α being supported by the shoes h^2 in the manner indicated in broken lines by said Fig. 3. After these operations the plate n is returned so as to carry the caps 2^a into position in proximity to the beam or rail A on which the racks c^1 are advanced by their pinions c^2 to pass the receptacles e laterally beneath the full bobbins α the slots between the receptacles e receiving the spindles, after which the receptacles e and other parts carried by the plate d are raised by the rack b^3 and wheel b^2 carrying the full bobbins upwardly until the bottoms of the receptacles e and the lower ends of said full bobbins are above the upper ends of the spindles 1 on which the receptacles e are moved by the lever f so as to bring the empty bobbins in the tube like parts e^3 of the receptacles vertically above the spindles 1. The racks b^3 are then lowered passing the empty bobbins γ over the spindles 1, this movement being continued until the receptacles e are below the lower ends of the bobbins thus placed on the spindles when said receptacles are withdrawn by the rotation of the pinions c^2 . The shaft h is then oscillated to allow the empty bobbins to fall upon the upper ends of the wharles 4 and the rail n again advanced to cause the caps 2 to occupy positions vertically over the spindles 1. The spindle rail B is raised sufficiently for the spindles 1 to support said caps 2 after which said rail n is returned in proximity to the bar or beam A. The spindle rail B is then lowered to the spinning position and the lifter 3 raised. The receptacles e are then shifted to carry the full bobbins supported thereby to positions opposite to the spindles 1 and the rod v turned over so as to rest upon the threads extending to said full bobbins, so as to sever them on the rotation of the empty bobbins γ . 65 During the descending of the lifter rail

B the dividing plates or tins s will be raised into the position shown by Fig. 3 and returned to their normal positions on the raising of said rail B in the manner hereinbefore described.

Such being the nature and object of our said invention what we claim is:—

1. In a machine of the character described, the combination with a series of spindles, a series of bobbin receptacles supported at one side of the spindles, means for effecting relative vertical and lateral movement between the spindles and bobbin receptacles, and means for moving the receptacles longitudinally of the series of spindles. 70

2. In a machine of the character described, the combination of a series of spindles, a series of bobbin receptacles supported at one side of the bobbins, means for moving the receptacles to and from a position over the spindles, means for effecting relative vertical movement between the spindles and receptacles, and means for moving the receptacles longitudinally of the series of spindles. 85

3. In spinning, doubling, twisting and like machines, a series of spindles, a series of caps loosely mounted thereon, and bifurcated supports for said caps, the extremities 95 of said bifurcated parts being deflected upward for retaining said caps in position.

4. In spinning, doubling, twisting and like machines, the combination of a series of spindles, a series of caps mounted thereon, 100 a series of supports for said caps, a bar carrying said cap supports, and a series of separators carried by said bar.

5. In spinning, doubling, twisting and like machines, a series of bobbins, receptacles 105 for said bobbins, curved parts forming vertical walls in said receptacles having openings for the passage of the spindles, plates forming the bases and side walls of said receptacles, a bar carrying said receptacles, 110 and means for moving said bar longitudinally to vary the relative positions of the several spindles and receptacles.

6. In spinning, doubling, twisting and like machines, a series of spindles, a rail 115 supporting said spindles, caps mounted on said spindles, supports for said caps, a series of bobbins fitting over said spindles, means for rotating said bobbins, a lifter plate for traversing said bobbins, means for supporting said bobbins on said spindles during doffing operations, a series of receptacles having one set of compartments for the reception of full bobbins, and one set of compartments for the reception of the empty 120 bobbin, means for supporting and traversing said receptacles, a series of separators, supports therefor, and a connection between said supports and the spindle rail.

7. In spinning, doubling, twisting and 130

like machines, a series of spindles, bobbins for taking over said spindles, a series of receptacles having two sets of compartments, one set being for empty bobbins, and the 5 other set for full bobbins, said receptacles being formed of sheet metal plates shaped to form the series with curved vertical walls, slots in said walls and base pieces of the receptacles, certain of these slots being 10 formed by one section having a notch fitted against a neighbouring section having a complete base piece, means for raising and lowering said receptacles, traversing them to positions above the spindles, and means for 15 moving them so that one series may at one time occupy positions over the spindles and at another time the other set or series will

occupy positions vertically over said spindles.

8. In a machine of the character de- 20 scribed, the combination with a series of spindles, of a series of bobbin receptacles including a series of holders for empty bobbins, corresponding in number to the spindles, and having means between said holders 25 for engaging bobbins on the spindles, and means for effecting relative lateral and vertical movements between the spindles and receptacles to carry filled bobbins from alignment with the spindles and position 30 empty bobbins in alignment therewith.

ALFRED STELL.
JOHN STELL.
